UNITED STATES PATENT OFFICE

148,397

DESIGN FOR A NAME PLATE FOR MOTORCYCLES

Clifford Brooks Stevens, Milwaukee, Wis., assignor to Harley-Davidson Motor Company, Milwaukee,
Wis., a corporation of Wisconsin

Application October 11, 1946, Serial No. 133,891

Term of patent 7 years

(Cl. D1—12)

To all whom it may concern:

Be it known that I, Clifford Brooks Stevens, a citizen of the United States, residing at Milwaukee, in the county of Milwaukee and State of Wisconsin, have invented a new, original, and ornamental Design for a Name Plate for Motorcycles, of which the following is a specification, reference being had to the accompanying drawing, forming part thereof.

In the drawing:

I claim:

The ornamental design for a name plate for motorcycles, as shown.

CLIFFORD BROOKS STEVENS.
